UNITED STATES PATENT OFFICE.

HARRY M. TEMPLE AND PHILIP KEARNEY, OF DETROIT, MICHIGAN.

DESIGN FOR AN END-CLOSURE FOR CONDUITS.

51,893.

Specification for Design.

Patented Mar. 19, 1918.

Application filed December 18, 1916. Serial No. 137,735. Term of patent 14 years.

To all whom it may concern:

Be it known that we, **HARRY M. TEMPLE** and **PHILIP KEARNEY**, citizens of the United States of America, residing at Detroit, in the county of Wayne and State of Michigan, have invented a new, original, and ornamental Design for End-Closures for Conduits, of which the following is a specification, reference being had to the accompanying drawings, forming a part thereof.

The figure shows a perspective view of

an end closure for electrical conduits embodying our new design.

We claim:

The ornamental design for an end closure for conduits as shown.

HARRY M. TEMPLE.
PHILIP KEARNEY.

Witnesses:

HORACE E. ALEXANDER,
JOHN F. CAMERON.
